UNITED STATES PATENT OFFICE.

LEVI M. BOWMAN, OF FORT WORTH, TEXAS, ASSIGNOR OF ONE-EIGHTH TO J. R. PENN AND ONE-EIGHTH TO J. O. PHILLIPS, BOTH OF FORT WORTH, TEXAS.

MODIFYING MEANS FOR HEADLIGHTS.

Application filed September 7, 1923. Serial No. 661,430.

To all whom it may concern:

Be it known that I, LEVI M. BOWMAN, a citizen of the United States, residing at Fort Worth, in the county of Tarrant and State of Texas, have invented certain new and useful Improvements in Modifying Means for Headlights, of which the following is a specification.

My invention relates to improvements in headlights in motor vehicles; and the objects are to provide means for conserving all the light emanating from the light-giving element and directing the same where it is most needed and at the same time serving as anti-glare means for protection against accidents. It must be understood that my invention is not a dimming proposal. All the light is needed and I have invented devices that have stood the severest tests and have been demonstrated to be highly efficient. Another object was to provide devices which can be applied to standard headlight fixtures as well as to new designs at small expense. Another object was to provide devices which comply with the requirements of the various regulations of the States of the United States. Other objects and advantages will be fully explained in the following description, and the invention will be more particularly pointed out in the claims.

Reference is had to the accompanying drawings which form a part of this application.

Fig. 1 is a front elevation of the improvements detached from the headlight.

Fig. 2 is a side elevation of the same.

Fig. 3 is a horizontal section of a reflector, its housing, the lens, and a plan view of one of the deflecting vanes and showing the means for holding the improvements in place.

Fig. 4 is respectively a front edge, a plan view, and a rear edge view of a vane.

Fig. 5 is a broken view of the locking and retaining ring.

Fig. 6 illustrates a variation in the vanes and the spacing means.

Fig. 7 is a plan view of one of the vanes shown in Fig. 6.

Similar characters of reference are used to indicate the same parts throughout the several views.

This invention includes a central flat relatively thin vane 1 which is horizontally dis-

posed and a plurality of vanes 2 which are relatively thin and provided with flat, parallel, horizontal surfaces. The vanes are locked together by a ring 3. The ends 4 of the vanes are shaped to conform to the contour of the reflector 5 which is enclosed in a housing 6, being generally beveled at the ends. The beveled portions of the vanes are rabbeted to form engaging bases for the ring 3 and tongues 7 are formed in the rabbets for locking purposes. The ring has kerfs or notches 8 to engage the tongues 7. When the ring 3 is forced on the tongues 7, the vanes will be locked in spaced relation and the ring may be soldered to the vanes. 60 65 70

The spacing means for the vanes are made to perform an additional function. Each vane 2 has a central off-set portion 9 which is in a plane parallel to the non-off-set portions. The spacing members 10 are 75 formed at angles to the lengths of the vanes. See Fig. 4. The spacers 10 form deflecting surfaces for deflecting light towards the front wheel of the vehicle. The spacers diverge towards the front forming 80 85 deflecting surfaces 11 for throwing portions of the light outwardly.

Provision is made for holding the light modifying means in the reflector 5. Narrow metallic strips 12 are attached to the top and bottom vanes and narrow springs 13 are riveted to the strip frame members 12. The springs 13 bear against lens 14 and against the front edges of the vanes. Fig. 2 shows position of springs 13 when put on the vanes 90 and Fig. 3 shows the position after the device is mounted in the headlight. The springs 13 hold the device in place and prevent rattling.

Figs. 6 and 7 illustrate a variation in the spacing means. Tongues 15 are struck from the vanes 2 and bent at right angles thereto to bear against the next adjacent vane. 95

To get the best results the vanes must be properly spaced and have the proper depth 100 from front to back. The best results have been obtained by spacing the vanes one-eighth of an inch apart and making the depth of the vanes from front to back $1\frac{1}{8}$ inches. This arrangement is uniform throughout. Variations may be made, but the above proportions should be maintained. The under sides of the vanes are polished so that they will deflect the light downwardly and not upwardly. The object is to prevent light 105 110

rays from powerful headlights from going as high as the eyes of the approaching pedestrians and drivers of approaching vehicles. The light modifying means herein set forth have been thoroughly tested under service conditions and found to be highly efficient. There may be other variations without departing from my invention. The upper sides of the vanes may be painted, if preferred.

What I claim, is:—

1. In a headlight provided with a reflector and lens and a light-giving element; a series of thin vanes horizontally disposed across the axis of the light-giving element behind the lens and having the ends thereof beveled to conform to the interior contour of said reflector and having rabbets in said beveled ends and a binding ring engaging said vanes in said rabbets and fixedly connected to said vanes.
2. In a headlight provided with a reflector and lens and a light-giving element; a series of thin vanes horizontally disposed across the axis of said light-giving element behind said lens and having the ends thereof beveled to conform to the interior contour of said reflector and having rabbets formed in said beveled portions and projecting tongues in said rabbets, and a binding ring countersunk in said rabbets and having kerfs engaging said tongues.
3. In a headlight provided with a reflec-

tor and lens and a light-giving element; a series of relatively thin vanes horizontally disposed across the axis of said light-giving element behind said lens and the central portions thereof being off-set in parallel planes and forming spacing members at angles to the width of said vanes and the exterior inclined surfaces of said spacing members forming means for deflecting light laterally.

4. In a headlight provided with a reflector and lens and a light-giving element; a series of relatively thin vanes horizontally disposed across the axis of said light-giving element behind said screen and having the ends thereof beveled to conform to the contour of said reflector and provided with spacing members integral therewith and a binding ring countersunk in the beveled portions of said vanes and fixedly connected to said vanes.

5. In a headlight provided with a reflector and lens and a light-giving element; a series of relatively thin vanes horizontally disposed across the axis of the light-giving element behind said lens and having the central portions thereof off-set in planes parallel to the vanes and forming spacing members, said spacing members diverging from back to front for deflecting light laterally.

In testimony whereof I set my hand, this 31st day of August, 1923.

LEVI M. BOWMAN.
